UNITED STATES PATENT OFFICE

2,114,355

BUCKLE

Frederick A. Ray, West Hollywood, Calif.

Application October 28, 1936, Serial No. 107,969

10 Claims. (Cl. 24—173)

My invention relates to a buckle of the particular type generally used in connection with belts, harness straps and the like, and the principal object of my invention is, to provide a relatively simple, strong, efficient and compact buckle, that is inexpensive of manufacture, presents a neat and finished appearance, and the parts of which buckle are capable of being easily and quickly connected and disconnected.

10 A further object of my invention, is to provide a buckle of the type having a body formed in two parts, one of which carries a fixed stud or studs that engage in apertures formed in the belt or strap to which the buckle is applied, and the 15 stud-carrying body member being retained in its belt-engaging position by the other body member of the belt which overlies a portion of the stud-carrying member and the natural pull or strains on the belt or strap tending to maintain the partition of the buckle in properly connected relation.

20 A further object of my invention, is to provide a buckle of the character referred to, that is very compact so that very little width and thickness is added to the over-all dimensions of the belt or 25 strap to which the buckle is applied.

With the foregoing and other objects in view my invention consists in certain novel features of construction and arrangements of parts that will be hereinafter more fully described and claimed and illustrated in the accompanying drawing in which:

30 Fig. 1 is a plan view of a buckle constructed in accordance with my invention, and showing the same applied to the end portions of a belt or strap.

35 Fig. 2 is a longitudinal section taken on the line 2—2 of Fig. 1.

Fig. 3 is an enlarged cross-section taken on the line 3—3 of Fig. 1.

40 Fig. 4 is a cross-section taken on the line 4—4 of Fig. 1.

Fig. 5 is a horizontal section taken approximately on the line 5—5 of Fig. 2.

Fig. 6 is a plan view of a modified form of the 45 buckle.

Fig. 7 is a longitudinal section taken on the line 7—7 of Fig. 6.

Fig. 8 is a horizontal section taken approximately on the line 8—8 of Fig. 7.

50 Fig. 9 is a plan view of a further modified form of the buckle of the type wherein one of the parts of the buckle body carries a plurality of strap-engaging studs.

Fig. 10 is a longitudinal section taken on the line 55 10—10 of Fig. 9.

Fig. 11 is a horizontal section taken approximately on the line 11—11 of Fig. 10.

Referring by numerals to the accompanying drawing, and particularly to the form of buckle illustrated in Figs. 1 to 5 inclusive, 10 designates a plate that is preferably formed of metal and substantially rectangular in form, and depending from the sides of this plate are narrow walls 11. Formed integral with the lower edges of these side walls at one end thereof, are inwardly presented lips 12 which occupy positions substantially parallel with and a short distance below the corresponding end portion of the plate 10.

10 At the opposite end of plate 10, a transverse portion is depressed so as to form a lip 13 that occupies 15 a plane just below that occupied by the main body portion of plate 10, and secured to and depending from this depressed lip, are one or more strap-engaging studs 14.

20 Adapted to overlie the depressed lip 13, is a strap 15 preferably formed of metal, the length 20 of which is substantially equal to the width of plate 10, and at the ends of said strap 15, portions thereof are extended downwardly, as designated by 16, which parts are in alignment with the depending side walls 11 of plate 10 and from the lower ends of said depending portions 16, the end portions of the metal strap forming the overlying member 15 and end walls 16 are extended inwardly to form lips 17 that are arranged parallel 25 with and spaced apart from the end portions of the overlying member 15.

30 When the two parts of the buckle are properly assembled to close or secure the buckle, strap 15 overlies the depressed end portion 13 of plate 10.

35 The intermediate portion of a piece of thin resilient metal that is folded double, lies immediately above and below the lips 12, as designated by 18, and the doubled portions of this piece of metal are secured to each other at points adjacent those 40 portions that overlie the lips 12 by suitable fastening means, such as rivets 19.

45 The intermediate portions of the two thicknesses of resilient metal that overlie the ears 12 are cut away so as to form at the sides of the resilient member, pairs of arms 20 that are disposed lengthwise of the buckle at the sides thereof, said arms being positioned above and below the inwardly projecting ears 17 and extending a short distance beyond said ears, and the ends 50 of these arms are connected by integral cross members 21.

55 Inasmuch as the metal from which the parts 18 and 20 are formed is resilient, the pairs of arms 20 which extend above and below the inwardly 55

presented lips 17 will yieldingly resist any tendency of said lips to tilt or swing so as to separate the members comprising the resilient arms 20.

5 When this form of buckle is secured to a strap, one end of the latter is formed into a loop 22 that passes around the transverse end members 21 that connect the ends of the resilient arms 20, and the free end of said strap is secured to the 10 body of the strap in any suitable manner, preferably by means of one or more rivets such as R.

When this form of buckle is used on a belt, one end of the latter is connected to the transverse members 21, and the opposite end portion of the 15 belt which is provided with spaced apertures 23, passes beneath the overlying member 15 and the body 20, with the stud 14 positioned in one of the apertures 23.

When the buckle is closed the end of stud 14 20 projects entirely through one of the perforations 23 in the end of the belt, and the projecting end of said stud engages against the cross member that connects the ends of the arms 20 opposite the transverse members 21, as illustrated by solid 25 lines in Fig. 2 and by dotted lines in Fig. 5.

When the bolt to which my improved buckle is applied, is in service, the pulling strains impressed on the connected ends of the belt tend to maintain the parts of the buckle in properly connected relation, for the pulling strains impressed on the resilient arms 20 are transmitted to member 15 so as to hold the same firmly in position over the depressed portion 13 that carries the belt-engaging stud 14, and the pulling 35 strains impressed on the perforated end portion of the belt directed against the stud 14 maintains the depressed end portion 13 of plate 10 beneath the overlying strap 15.

To disconnect the parts of the buckle, the ends 40 of the strap or belt that are connected by the buckle are drawn toward each other, so as to move the buckle members 10 and 15 away from each other, and when member 15 has been moved into position so as to wholly uncover the underlying depressed member 13, the end of plate 10 carrying said depressed member and the stud 14 is swung upward a sufficient distance to disengage stud 14 from the aperture 23 in which it was engaged.

50 During this swinging or tilting movement of member 10, the ears 12 disposed between the pairs of resilient legs 20 function as an axis on which member 10 moves and the members of the pairs of resilient legs 20 are yieldingly forced apart to 55 accommodate the movement of the ears 12, and after the belt or strap has been disengaged from the stud 14, the member 10 will be swung toward the perforated end of the belt by the pressure of the resilient legs 20 against the ears 12.

60 In order that this form of buckle may present a balanced appearance, the upper or outer face of plate 10 is provided with a transverse groove G adjacent the end opposite the end having the depressed lip 13, and thus when the buckle is 65 properly connected, the front face thereof appears as a rectangular panel with parallel grooves disposed adjacent the ends of the buckle body.

In the modified form of buckle illustrated in Figs. 6 to 8 inclusive, the main body portion of the buckle comprises a plate 24, one side edge of 70 which is slightly depressed, as designated by 25, and adapted to overlie this depressed portion 25 is a plate 26 that is approximately equal in length to the length of plate 24.

75 Depending from the ends of plate 26 are short

end members 27, and projecting at right angles inwardly toward each other from the lower ends of said end members 27 are ears 28.

Depending from the ends of plate 24 are end walls 29, and projecting at right angles inwardly from the lower portions of these end walls 29 are ears 30. The depressed portion 25 of plate 24 carries one or more studs 31 that are adapted to engage in the perforations of a belt or strap B. A thin plate of resilient metal is bent double to 10 form practically identical upper and lower members 32, and positioned between said members adjacent the point where the sheet of metal is bent are the ears 28 that project inwardly from the lower ends of the end walls 27.

15 The ears 30 that project inwardly from the lower ends of the end walls 29 are positioned between the layers or parts of the resilient plate, and formed in the end portions of the members 32 beyond the ears 30 are coinciding apertures 33. 20 The transverse members 34 at the outer end of aperture 33 combine to form a cross-bar or the like, around which is looped one end of the belt or strap B and the portions thereof adjacent this cross-bar being united in any suitable manner; 25 for instance, by a rivet or rivets or by a transverse row of stitches.

30 Formed in the upper one of the members 32 adjacent the end where the same is bent, is a longitudinally disposed slot 35 for the accommodation of the lower end of stud 31 when the buckle is closed, see Fig. 7.

35 Where this form of buckle is used, the pulling strains impressed upon the connected parts of the belt or strap tend to hold the parts of the buckle in assembled relation and with plate 26 overlying the depressed portion 25 of plate 24, so as to hold the parts of the buckle together and with the stud 31 in one of the apertures of the belt or strap.

40 To disconnect this form of buckle, the connected ends of the belt or strap are moved toward each other, thereby moving the parts of the buckle away from each other or until the depressed portion 25 of plate 24 is free from overlying plate 26, and under such conditions the depressed end of plate 24 may be swung away from the perforated portion of the belt or strap so as to disengage the stud 31 from the aperture in which it has been positioned.

50 During this swinging movement of the buckle member carrying stud 31, the ears 30 positioned between the sides of the resilient members 32 function as an axis, and after the belt or strap has been disengaged from the stud 21, the pressure of the resilient members 32 on the interposed ears 30 acts to return the buckle member carrying the stud 31 to its normal position.

55 The modified construction illustrated in Figs. 9, 10 and 11 is embodied in the larger size of buckles or those intended for use in connection with harness or for equipment having comparatively large and heavy straps. This form of buckle comprises a loop having an upper or outer plate 36 and a lower or inner plate 37, the latter 65 being slightly wider than the plate 36.

60 Associated with this loop is a buckle member comprising an upper or outer plate 38, one side portion of which is depressed to form a lip 39, which when the parts of the buckle are connected, lies beneath the plate 36 of the loop.

70 Seated in and depending from underlying lip 39 are two or more studs 40 that are adapted to engage in apertures 41 that are formed in a strap s that passes through the buckle imme- 75

diately beneath the plate 38 and its depressed lip 39.

Depending from the ends of the plate 38 are end members 42, and connecting the lower ends of these end members is a transverse bar 43 that normally occupies a position directly in front of plate 37. Arranged beneath the plates 37 in any suitable manner, preferably by means of a rivet 44, is a centrally arranged strip 45 of resilient metal which projects a short distance beyond strap or plate 43 and the end of said strap 45 terminating in a hook 46. One end of a resilient metal strip 47, which overlies plate 43, is secured to plate 37 by the rivet 44, and the free end of this strip 47 terminates adjacent the hook 46 on strip 45. Thus the transverse plate or strap 43 is positioned to move freely between the resilient strips 45 and 47 and said strips function as springs, and yieldingly resist any tendency of the strap or plate 43 to tilt in either direction.

Overlying and underlying the plates 37 and 43 and the resilient strips 45 and 47 that are carried by plate 37, are the ends of straps *s*, the ends of which are suitably secured to each other at a point just beyond the outer edge of plate 37, and which securing means may be rivets or a transverse row of stitching as illustrated in Figs. 10 and 11.

In this form of buckle, the pulling strains impressed on the straps *s* and *x* tend to hold the parts of the buckle in assembled relation and with the plate 36 overlying the lip 39 and the latter carrying the studs 40 that engage in the apertures of strap *s*.

To disconnect this form of buckle, the connected ends of the straps *s* and *x* are moved toward each other for a short distance or until lip 39 has been disengaged from its position beneath plate 36, and the plate 38 carrying the lip may now be swung upward so as to disengage the studs 40 from the apertures 41 in which they have been engaged, and this movement of plate 38 is yieldingly resisted by the resilient strips 45 and 47, between which the strap or plate 43 is positioned.

After the strap *s* has been disengaged from the buckle, the pressure of the resilient strips 45 and 47 on strap or plate 43 acts to swing the parts 38 and 39 of the buckle back to their normal positions.

Thus it will be seen that I have provided a buckle that is relatively simple in construction, inexpensive of manufacture and very effective in performing the functions for which it is intended.

The buckle is very compact, and therefore adds very little to the thickness of the strap or straps with which it is associated, and when the buckle is closed so as to secure the ends of a belt or strap, all pulling strains tending to separate the connected ends of the belt or strap are utilized for holding the parts of the buckle in proper assembled relation, thus making it impossible for the parts of the buckle to become separated while the connected ends of the belt or strap are under pulling strains.

In the construction illustrated in Figs. 1 to 5, inclusive, the lower end of the stud 14, when the buckle is closed, engages against the cross member that connects the ends of the resilient arms 20 opposite the transverse arms 21, and thus both ends of the stud have firm rigid bearings that transmit all pulling strains of the perforated end of the belt or strap to the plate 10 and the doubled member 18 that provides the resilient arms 20 and which is connected to plate 10.

In the construction illustrated in Figs. 6 to 8

inclusive, the end of the stud 31 that projects through the perforation in the strap bears against the end of the slot 35 in the upper end of members 32, thus transmitting all pulling strains on the strap to the body 24 of the buckle and the plates 32.

In my improved buckle the stud or studs that engage in the perforations of the belt or strap project through the latter at right angles and thus the strap or belt is engaged and held in a practically straight line, particularly at the point of application of strains and stresses, without marring or bending the leather at the point of connection, and as the body of the buckle comprises two cooperating transverse loops that pass around the belt or strap at the point of application of strains, the belt or strap is protected from spreading and bulging at the point of connection.

Obviously, my improved buckle may be advantageously employed wherever it is desired to detachably connect or unite two straps or the ends of a single strap, such as a belt, and in addition to presenting a neat and finished appearance the buckle provides an exceptionally strong, durable, efficient and easily manipulated connection for all straps, belts and the like.

It will be understood that minor changes in the size, form and construction of the various parts of my improved buckle may be made and substituted for those herein shown and described without departing from the spirit of my invention, the scope of which is set forth in the appended claims.

I claim as my invention:

1. In a buckle, a pair of cooperating body members adapted, when engaged with one another, to receive a strap, a strap-engaging stud carried by one of said body members, a pair of resilient members secured to and projecting from the lower portion of the other one of said body members and means secured to the stud-carrying body member and passing between said resilient members to form a sliding fulcrum for said stud-carrying body member when the latter is disengaged from the other body member.

2. In a buckle, a pair of cooperating body members adapted, when engaged with one another, to receive a strap, a strap-engaging stud carried by one of said members, a pair of resilient members secured to and projecting from the lower portion of the other one of said body members, means secured to the stud-carrying body member and passing between said resilient members to form a sliding fulcrum for said stud-carrying body member when the latter is disengaged from the other body member and a portion of which stud-carrying body member underlies a portion of said second mentioned body member when the parts of the buckle are properly connected.

3. In a buckle, a pair of cooperating body members having releasably interengaging parts and adapted when connected to receive a strap, resilient members secured to and projecting from one of said body members, means projecting from the other body member and passing between said resilient members and a strap-engaging stud carried by the sliding and swinging body member.

4. In a buckle, a pair of cooperating body members having releasably interengaging parts and adapted when connected to receive a strap, resilient members secured to and projecting from one of said body members, means projecting from

- the other body member and passing between said resilient members and a portion of one of which body members underlies a portion of the other body member when the parts of the buckle are closed and in engagement with a strap.
5. In a buckle, the combination with a belt receiving loop and a pair of substantially parallel resilient members secured to and projecting from a portion of said loop, of a buckle member mounted for sliding and tilting movement upon said resilient members and having a portion that is adapted to underlie a portion of said loop when the parts of the buckle are in closed position.
6. In a buckle, the combination with a belt-receiving loop and a pair of substantially parallel resilient members secured to and projecting from a portion of said loop, of a buckle member mounted for sliding and tilting movement upon said resilient members, having a portion that is adapted to underlie a portion of said loop when the parts of the buckle are in closed position and a belt-engaging stud carried by the underlying portion of said sliding and tilting buckle body member.
25. 7. In a buckle, the combination with a belt-receiving loop and a pair of substantially parallel resilient members secured to and projecting from a portion of said loop, of a buckle member mounted for sliding and tilting movement upon said resilient members, having a portion that is adapted to underlie a portion of said loop when the parts of the buckle are in closed position, a belt-engaging stud carried by the underlying portion of said sliding and tilting buckle body member and said resilient members being provided with openings for the reception of a strap or the like.
8. In a buckle, a pair of cooperating body members adapted to receive a strap, resilient members secured to and projecting from one of said body members and engaging a part of the other body member to form a sliding fulcrum between said members, a strap engaging stud projecting at right angles from one of said body members, the end of which stud is adapted to engage one of said resilient members when the buckle is closed, and a portion of the body member that carries said stud occupying a position beneath the other body member when the buckle is closed.
9. In a buckle, a pair of cooperating body members adapted to receive a strap, resilient members secured to and projecting from one of said body members and engaging a part of the other body member to form a sliding fulcrum between said members, a strap engaging stud projecting at right angles from one of said body members, the end of which stud is adapted to engage one of said resilient members when the buckle is closed, a portion of the body member that carries said stud occupying a position beneath the other body member when the buckle is closed, and said resilient members being provided with openings for the reception of a strap or the like.
10. In a buckle, a pair of cooperating body members having releasably interengaging parts and adapted, when connected, to receive a strap, resilient members secured to and projecting from one of said body members and means projecting from the other body member and extending between said resilient members to form a sliding fulcrum between said members.

FREDERICK A. RAY.
